UNITED STATES PATENT OFFICE

ERNST HERMANN JÄHNE, OF DRESDEN, GERMANY, ASSIGNOR TO THE FIRM "UNIVERSALE" CIGARETTEMASCHINEN-FABRIK J. C. MULLER & CO., OF DRESDEN, GERMANY

APPARATUS FOR ALIGNING MATCH STRIPS HAVING STAGGERED MATCHES

Application filed August 30, 1929, Serial No. 389,518, and in Germany August 31, 1928.

The present invention relates to a device for separating and straightening strips provided with matches arranged in staggered relation to one another, which are to be conveyed to the packaging machine.

Machines are known which produce strips consisting usually of cardboard and containing matches arranged in staggered relation to one another and provided with ignitable tips. During subsequent operations the well-known flat match packets or books are formed which can be carried in the pocket, the steps in the process consisting in separating the strips into sections of equal length, in stacking these sections and in combining them by stitching into a covered unit provided with a friction surface. These steps are carried out by a special machine into which several (usually two or three) stacked and correspondingly straightened strips are fed.

Considerable difficulties are experienced in separating the strips and in stacking them accurately so that they are in perfect register, because the strips are difficult to handle owing to the staggered arrangement of the matches and the presence of the thick ignitable tips. Above all, the strips are difficult to displace relative to one another.

The problem of preparing the strips coming from the producing machine for the packaging machine by separating them and straightening them out is solved according to the present invention by placing the strips arranged as they come with straightened tips on a conveyor moved forward transversely to the longitudinal direction of the strips one above the other on a multisteped slide which, at a stroke in the feed direction of the conveyor, carries at first the lowest strip on a rake to a fixed stop, whereupon a controlled covering plate consisting of sheet metal and the like is placed over this strip and the slide during its further movement pushes a second strip caught by it onto the covering surface as far as the first one. In addition, lateral guides are provided to straighten the strips during their forward movement so that their side edges are in perfect alinement, and the stacked and perfectly alined strips are then caught jointly and conveyed in their longi-

tudinal direction towards the device which separates the strips into sections and provides these sections with covers.

Preferably the rear portion of the slide consists of a guide member 7 having an oscillatory front part 6 which latter by spring actuation is guided on a control surface 15 so that after reaching any feed position for one strip it is lowered to such an extent that the next slide step can pass under the strips deposited.

Within range of the feeding means ending above the slide a spring-actuated stop is arranged at a corresponding distance above the slide so that after the pile of strips has reached a certain height the subsequently arriving strips are retained by a spring-urged stop and the enlargement of the pile is thus prevented.

In this manner the conveyor may be supplied continually and the height of the pile of strips deposited by the conveyor remain constant.

One embodiment of the invention is illustrated in the accompanying drawings, in which Figure 1 is a cross section of the machine;

Fig. 2 is a top plan view thereof;

Fig. 3 is a side elevation partly in section of Fig. 1 seen from the right hand side of Fig. 1; and

Fig. 4 is an enlarged view of a detail.

Referring to the drawings, the strips are deposited on the conveyor 1 moving in the direction of the arrow and being guided over the rollers 2 and 3 so that their ignitable tips are in front. The conveyor 1 carries the strips to the stop 4 and piles them up there. To prevent the pile from getting too high, which would cause the strips to tumble over and move on in wrong position, a spring-urged stop 5 is provided above the pile to prevent the further growth of the pile. The subsequently arriving strips are thus caused to remain on the conveyor passing under them. (See the two top strips in Fig. 1).

Underneath the pile of biparted and multi-stepped slide 6, 7 moves to and fro. The rear portion 7 of the slide is a sliding piece guided in the ways 8 not shown. The member 7

is engaged by a rod 9 connected with one end of the double-armed lever 11 arranged at 10. A cam 12 controls the double-armed lever 11 and thus the slide 6, 7.

- 5 The front portion 6 of the slide is articulated at 13 to the member 7 and carries at its front part a roll 14 running on a step-like surface 15. The member 6 is pivoted about its point of articulation 13 by means of the roller 14 which is attached to its front end and which by the tension spring 31 is retained in contact with the cam or control surface 15.

15 In the modification shown, in which two strips are to be superimposed, the slide 6, 7 is provided with the two steps 16, 17, one of which is secured to the member 6 while the other one is formed by the front edge of the sliding piece 7.

20 During its working stroke the slide 6, 7, by means of the step 16, takes first a strip from the pile and pushes it on a support 18 up to the stops 19 which engage both ends of the strip.

25 The double-armed lever 21 controlled by the cam 20 and pivoted at 22 carries at its free end the covering plate 23, the front end 24 of which is preferably bent slightly downwardly.

30 The covering plate 23 is controlled so that it will be lowered to the strip at the moment when the latter has reached the stops 19.

Simultaneously, the roll 14 has passed the step of the surface 15. The member 6 of the 35 slide is lowered, the step 16 continues its movement under the support 18, and the slide catches the second strip by means of the step 17, the second strip being pushed onto the covering plate 23. Both strips are guided during their forward motion by the lateral guides 25, 26 so that they exactly cover one another, while the covering surface prevents the interlocking of the staggered rows of matches to make possible the lateral 40 displacements caused by the guides 25, 26 in order to bring the strips into alignment.

45 After the two strips have been brought into absolute alignment in the way described, a gripper 28 provided with the pins 27 begins to act by getting hold of the two superimposed strips and feeding them by sections into the cutting device 29, 30. The stroke of the gripper 28 is timed so that the cutters 29, 30 always strike one of the separating lines 50 provided on the strip.

The pieces separated by the cutting device 29, 30 are then guided in any suitable manner to a device which provides them with covers.

55 The upper knife 30 is mounted on an arm 60 31' of a slidable member 31 which latter is reciprocally movable in a channel 32 provided on a portion of the machine frame G. To reciprocate said member 31 there is pivotally connected at 33' to said member a crank arm 65 33 provided near its free end with a slot 33''

in which the shaft 34 of the machine is freely movable. A roller 35 on said arm 33 tracks a cam 36 mounted on shaft 34. A spring 37 attached to the arm 33 at 37' and to the frame G as at 37'' maintains rolling contact between roller 35 and cam 36.

70 The pins 27 on the gripper 28 are given their requisite movement as follows:

Gripper 28 is carried on an arm 38 (see Fig. 4) of the double-armed lever 38-39. Said lever at 40' is pivotally connected to an arm 40'' which latter is mounted to a slider 40. The latter is reciprocally movable on and attached to the machine frame. A suitable pin 42 is engaged by the fork arm 43' of a lever 43 which latter at 44 is suitably pivoted to the machine frame. The lever 43 is provided with a roller 43'' which tracks a cam 45 mounted on shaft 34. A spring 46 suitably attached to said lever and to said machine frame serves to maintain the engagement of roller 43'' and cam 45.

80 The free arm 39 of the double-armed lever 38-39 rotatably engages a shaft 47 which is fixed to an operating member 48. The latter is vertically reciprocable but non-rotatable in a suitable guide 49 on the machine frame. The lower end of member 48 is provided with cam roller 48' which tracks a cam 50 on shaft 34. A compression spring 51 suitably mounted serves to maintain continuous engagement between member 48' and cam 50, and is mounted for example on member 48 between a shoulder 48'' thereon and the lower end of guide 49. Reciprocation of said member 48, causes rotation of arms 38 and 39 about their pivot point 40' so that said pins 27 on arm 28 are alternately moved into and out of engagement with the match strip.

90 The main drive of the machine is effected from the main driving shaft 52 which through pulley 53 mounted thereon is adapted to be driven by the suitably driven belt 54 or the like.

100 A link 55 having a slot 55' through which shaft 52 extends so that said link is freely slideable on said shaft is provided. A cam roller 58 on link 55 tracks a cam 59 mounted on shaft 52 and rotatable therewith. Spring 57 attached both to said link and to said frame G serves to maintain continuous contact between the latter and said cam 59. A double-armed lever 56 has one of its arms pivotally connected at 55' to link 55. The arm of said lever has pivotally attached thereto the pawl 60 which engages the ratchet wheel 61. The latter has connected thereto a disk 62 and the two are rotatably borne on a spindle 63 suitably supported from the machine frame. The pivoting point of lever 56 is also on said spindle 63. A cam 62' on disk 62 cooperates with the end 64' of a double-armed lever 64 which latter is pivotally borne at 65 on the machine frame. The forked end 64'' of lever 64 engages in an annular slot 66' provided

externally of a slidable bushing 66 keyed to shaft 67.

Said bushing has teeth 68 which may engage corresponding depressions in a second bushing 69 rotatably mounted on shaft 67. The coupling of said two bushings is controlled through manipulation of lever 64 by reason of cam 62'. A spring 70 serves to maintain continuous engagement between the end 64' and cam 62'.

Shaft 67 is adapted to be driven from main shaft 52 by means of gear wheels 71 and 72 mounted on said shafts and meshing with one another. Shaft 67 which is continuously rotated from shaft 52, is through chain drive wheels 73 and 74 and chain 75 coupled to shaft 76 on which the roller 3 over which conveyor 1 passes, is mounted.

Shaft 34 is driven from the main drive shaft 52 through the sprocket wheels 84 and 85 and chain 86.

On bushing 69, a sprocket wheel 77 is fixedly mounted and over which chain 78 passes. The latter also engages sprocket wheels 79 and 80. Wheel 79 is attached to suitably journaled shaft 81 on which cam 12 is also fixedly mounted. Wheel 80 is attached on the suitably journaled shaft 82, on which cam 20 is also carried and by which cover plate 23 is controlled.

The operation of the machine is as follows:—

As soon as a pair of match strips as is seen in Fig. 1 have been deposited on support 18 as previously described they are seized by pins 27 on gripper 28 and moved so that a package width of said strip are moved past knives 29 and 30 as shown in Fig. 2. Thereupon the upper knife 30, operated through cam 36, cuts off said package width of strip. Simultaneously gripper 28 is raised from said cut off portion by means of member 48 so that pins 27 are freed from said strip. The cut-off strips may fall upon a slanting surface 83 from which they are removed for further treatment. The above is repeated until the strips are divided as above described.

As soon as this is finished the projecting portions 62" of cam 62' engage the lower end 64' of lever 64 and cause engagement of bushings 66 and 69 whereupon sprocket wheel 77 becomes coupled with shaft 67 which will thereby be set in operation to feed a new set of strips onto support 18 and simultaneously cover plate 23 will be rotated to permit said strips to be so deposited and then returned to clamp said new strip in place.

The feeding ratio of links 54, 55 and sprocket wheel 60 and cam disk 62 should be such that it is always uniform and results in a number of ten matches being contained in each of the sections struck off from said match strips. To effect this the rotation of disk 62 should be $\frac{1}{10}$ as fast as that of shaft 52,

i. e. for each ten rotations of the latter shaft, disk 62 rotates once.

I claim:—

1. In a packing machine for strips provided with matches arranged in staggered relationship, a conveyor which is movable forwardly transversely to the longitudinal direction of the strips and is adapted to receive the strips with staggered tips, a multi-stepped slide adapted to receive from the said conveyor the strips which are deposited thereon in a pile, and to catch the lowermost strip during the stroke taking place in the feed direction of the said conveyor, means acting as support for the said lowermost strip caught by the said slide, stationary stops limiting the motion of the said slide and strip, a controlled covering plate adapted to be placed over the said strip and to receive an additional strip from the said slide in perfect alinement with the preceding one, lateral guides for straightening the said strips during their forward movement to bring them into perfect lateral alinement, means for catching the said superimposed and alined strips and conveying them in their longitudinal direction, and a device for separating the said strips into sections.

2. In a device according to claim 1 in which said multistep slide comprises a guide piece forming the rear portion of the said slide, an oscillatory part, attached to said guide piece and forming the front portion of the said slide, and a cam surface for guiding the said oscillatory part, said cam surface being so shaped that the said oscillatory part is lowered after each feed position of each strip to the extent to permit the next step of the said slide to pass under the previously deposited strip.

3. In a device according to claim 1, in which a spring-actuated stop is positioned at a distance above the said slide and is adapted to prevent the said strips from being piled up beyond a predetermined degree.

4. In a device according to claim 1, in which means for controlling said covering plate which is adapted to be placed between the said layers are provided and which means comprise a double-armed toggle, one arm of the said toggle being formed by the said covering plate, and a cam adapted to be engaged by the second arm of the said toggle, the fulcrum of the lever being in front of the said deposited match strips.

5. In a packaging machine for strips provided with matches arranged in staggered relation, a conveyor impelled forwardly transversely to the longitudinal direction of the match strips, movable means adapted to receive said strips from said conveyor in a pile and to move the lowermost strip of said pile forwardly, means for supporting said lowermost strip when so moved, means for positioning a second strip in lateral alinement

with said first named strip, means for conveying said alined strips in longitudinal direction and means for separating said alined strips into sections.

- 5 6. In a packaging machine for matches arranged on strips, means for depositing said strips in a pile, means for moving the lowermost strip of said pile forwardly onto a support, means for moving the next lowermost
10 strip from said pile over said first named strip, means for alining said strips laterally, and means for conveying said alined strips in longitudinal direction thereof preparatory to packaging said matches.
- 15 7. In a packaging machine for matches arranged on strips, means for depositing said strips in a pile, means for moving the lowermost strip of said pile forwardly into a support, means for moving the next lowermost
20 strip from said pile over said first named strip, means for avoiding interference between the matches on said two strips, means for alining said strips and means for conveying said alined strips to packaging means.
- 25 In testimony whereof I affix my signature.

ERNST HERMANN JÄHNE.
